UNITED STATES PATENT OFFICE

2,143,039

CABINET DISHWASHER

Edgar S. Stoddard, Berwyn, Ill., assignor to The Conover Company, Chicago, Ill., a corporation of Illinois

Application December 22, 1934, Serial No. 758,767

4 Claims. (Cl. 141—9)

This invention relates to improvements in dish-washing machines and more particularly to machines of the built-in or cabinet-type of machine disclosed in my earlier Patent No. 1,946,181.

5 The embodiment of my invention as shown in the accompanying drawings relates to the type of sink having a depressed basin portion and an adjacent drain board or storage portion beneath which a dishwashing compartment is located.

10 Heretofore in sinks of this kind it has been customary to have a dishwashing machine mounted under the drain board portion and to use the drain board as a sliding or lifting cover for the dishwasher so that ready access may be had thereto. This has necessitated the use of a two 15 or more piece drain board cover having necessary cracks and crevices for fitting the cover to the sink. Within these crevices dirt and food particles collect, causing decay and generally unsanitary sink conditions. Moreover, the drain 20 board portion cannot be used for storing dishes nor other kitchen supplies at certain periods when the machine is to be operated, because the board must be left free to be raised or slid away 25 from the dishwasher.

One object of my invention is to provide a cabinet-type dishwashing machine having a more pleasing appearance and easily adaptable to the modern kitchen.

30 Another object of my invention is to provide a cabinet-type dishwashing machine wherein the top surface may be permanently used as a table or drain board in connection with an adjacent sink.

35 A still further object of my invention is to provide ready access to the dish-holding apparatus within a cabinet-type dishwashing machine and to provide means for simplifying the loading and unloading of the same.

40 Still other and further objects of my invention will be pointed out or indicated hereinafter or will be apparent to one skilled in the art upon an understanding of the invention and its employment in practice.

45 In the drawings:

Fig. 1 is a sectional view of one embodiment of my apparatus taken on the line 1—1 of Fig. 3;

Fig. 2 is a view of my apparatus from the rear showing it partly in section and located within 50 its cabinet;

Fig. 3 is a view in elevation of a finished cabinet containing the present invention;

Fig. 4 is a view of the extensible and retractable dish rack holders as mounted within a cabinet 55 net;

Fig. 5 is a sectional view of the cabinet on the line 5—5 of Fig. 3;

Fig. 6 is a view of the cabinet door hinge structure showing the door in closed position;

Fig. 7 is a view similar to Fig. 6 showing the 5 door open; and

Fig. 8 is a sectional view through one of the extensible and retractable slides of the dish rack holders.

The present invention makes possible the use 10 of a solid one-piece sink and drain board surface unit. This result is accomplished by inserting a dishwashing unit having a side opening, beneath the sink drain board. When in open position, the door acts as a shield to prevent water from the 15 interior of the tank from running onto the floor. The dish racks within the tank are arranged upon telescoping slides which permit the racks to be slid outwardly from the tank and over the open water-retaining door. In this position the 20 racks may be easily loaded or unloaded and drying of the dishes by the evaporation of the hot water upon them is accelerated. The door is sealed at its edges to prevent leakage of water therethrough when the machine is in operation 25 and is hinged to the cabinet structure rather than to the tank so that the enamel finish of the latter is less likely to be chipped in assembly and the tank does not have to bear the weight thereof.

In the accompanying drawings my invention is 30 adaptable to a cabinet-type sink 10 such as disclosed in Fig. 3. This type of sink comprises the usual sink basin 11 with an integral adjacent drain board 12. The sides and ends of the sink 10 are enclosed, hiding the piping from view, affording a storage space beneath the sink, and generally creating a neat and pleasing appearance.

Beneath the drain board 12 is mounted a dish-washing machine apparatus of any well known 40 type accessible through a side opening rather than through a conventional swinging top cover. A downwardly swinging side door 14 is provided in the sink 10 wall for the tank 16 of the dishwasher. This door is preferably mounted upon the cabinet 45 structure itself for ease of assembly and affords a water-tight closure for the tank when closed and a drip shield for the dishes when open.

The opening through the cabinet wall into the tank 16 is substantially rectangular in shape, 50 and around the periphery of this opening is mounted a channel member 18 having a U-shaped cross section and containing a resilient gasket 19 of sponge rubber or the like. This gasket extends out of the channel member, which 55

should be wide enough and deep enough to hold a substantial cushion of rubber, so as to afford an effective seal with the door when the latter is pressed thereagainst. Upon the door itself is provided a continuous rib or raised portion 20 that follows the contour of the center line of the gasket 18 and is adapted to be pressed thereagainst upon closing the door to make an effective seal.

10 It has been found preferable to make the channel member 18, and consequently the gasket 18

and the rib 20, with rounded corners. When this is done the channel or trough 18 should be reduced in depth around the corner curves on the 15 outer edge to make up for the thinning of the gasket at this point as it is stretched therearound. Of course this can be remedied by padding the gasket at these points or the gasket may be moulded for this purpose.

20 Upon opening the door 14 water accumulated thereon tends to run downwardly upon the floor unless means are used to collect the same. In the present embodiment is shown an L-shaped drip trough 22 which is sealed at the bottom and

25 at both ends to the front of the cabinet adjacent the channel 18. The short leg of the L-shaped trough is turned upwardly and the bottom portion of the door 14 is adapted to fit in between this leg and the channel 18. Upon opening of the

30 door, the lower portion thereof continuously overhangs this upturned lip or leg of the trough 22 so danger of water dripping upon the floor is eliminated. The trough 22 is arranged to be drained by gravity and may be permanently connected to the interior of the dishwashing tank 16 by a tube 23 for this purpose.

A close fit is desired between the door 14 and the gasket to prevent leakage of water from the machine. When the door of the machine is 40 closed, channel 22 prevents escape of water. The position of this channel makes it necessary in opening the door 14 to lift the door over and out of the channel, hinging mechanism for this function being shown in Figs. 6 and 7. To carry out 45 both this lifting and swinging action, the point of pivot for the door hinge is spaced in front of the cabinet adjacent the trough 22. A system of semi-circular or arcuate hinges sliding in semi-circular guides or tracks is used.

50 The hinge members on each side of the machine are provided with a hinge plate having an inner hub portion 24 and an outer guide portion 26. The outer guide portion 26 terminates as shown at 27 to form a stop or limiting member 55 for the movable portion of the hinge. The hub portion 24 and outer guide 26 are joined on the outside of the hinge member 29 by a tie plate 28, as may be seen in the drawings.

Between the hub portion and outer guide the door hinge member 29 is slidably mounted. This hinge is attached at one end to the door 14 and at the other end is provided with a tall-like stop and spring connector 30 which cooperates with the stationary stop member 27 to prevent further outwardly swinging movement of the door 14, as shown in Fig. 7. In opening the door 14 the stop member 27 holds the movable hinge member 29 in position when a sufficient part of the member has passed around the inner hub to maintain a proper horizontal location of the door. It is preferred to construct the rotatable portions 29 of the hinges of two separate plates, one of which is attached to the door, and the other of which is attached to spring 32, as shown in Fig. 2. The

two plates may be connected together in any suitable manner to provide a rigid structure.

A spring 32 is attached at one end to the arm 30 and at the other end to a hook or staple 33 on the cabinet frame. To complete the door assembly 5 a latch device 35 is affixed to the upper central portion of the door, this latch, in combination with the hinge members on each side of the lower portion of the door affording a firm three point securement which is adequate to prevent leakage.

10 By constructing the hinge members with pivotal centers spaced from the machine, an eccentric action is provided which effects a lifting of the door as the latter is rotated toward the horizontal position shown in Fig. 7. As the door is closed, it also is lowered into the channel 22 to form a water-tight connection.

15 In some instances the setting of the hinge guides 24 and 26 may be adjusted to produce a 20 tighter closure at the bottom of the door than at the top, thereby causing the door to appear as though slightly open at the top although a tight seal is afforded. To give a more finished appearance in those instances the gasket channel 18 25 may be set at a very slight angle with reference to the vertical front wall of the cabinet—say $\frac{1}{8}$ inch in 22 inches—causing the door to fit evenly all the way around.

20 In adapting the tank 16 to the opening in the 30 cabinet the periphery of the opening in the tank 16 wall should be slightly larger and sized to fit tightly over or around the gasket channel 18. A further U-shaped tank opening gasket 40 is fitted over the edge of the tank opening and the 35 edge slipped over the outer wall of the gasket channel 18 and against the vertical portion 42 of the cabinet front to which the channel 18 is sealed (see Fig. 1). The tank is held in place over the channel 18 by means of clamp straps 40 that are pulled against the tank by long adjustable hooks 46 which are anchored into the cabinet frame at one end 48 and to the straps 44 at the other end 49. Rubber pads 50 are provided between the strap clamps 44 and the walls 45 of the tank 10 wherever said clamps and said walls come into contact to prevent chipping of the enameled tank wall.

25 In Figs. 1, 4 and 8 are shown the slideable dish 50 rack supports. These supports comprise front and rear brackets 51 and 52, respectively, between each pair of which is rigidly mounted an outer stationary slide tube 53. The brackets are bored to receive the inner telescoping slide tubes 54 which extend inwardly within the outer slide 55 tubes 53 and are slidably supported thereby. Upon the inner end of the inner slide tubes 54 are raised stop portions 55 which cooperate with shoulder portions 56 of the brackets 51 to prevent further outward movement of slides 54 from 60 within their bracket and outer slide 53. As the outer slide tubes are larger in diameter than the bored portion of the brackets 51 in order to provide the shoulders 56, the stop portions 55 of the inner slide tubes should be of sufficient size to 65 engage the outer tubes 53 in a snug fit. This will prevent any weaving or rattling between these telescoping tubes.

70 The basket support members comprise in part the front straps 57 having the inwardly projecting annular fittings 58 which are received within the outer end of the inner slide tubes 54. A threaded plug 59 driven into this end of the inner slide receives a bolt 60 which passes through the strap 57, the fitting 58 and into the plug 59 hold- 75

ing the assemblage together. At the rear of the outer slide tubes 53 are the rear straps 61 which are slidably mounted thereover by means of the ring members 62. A rack slide frame 63, substantially rectangular in shape and preferably having rounded corners, is supported by means of the front and rear straps 57 and 61 from the inner and outer slide tubes. Diagonally across the rounded corners of the frame 63 are the dish rack 10 or basket support bars 64.

The dish racks 65 themselves may be of any design adaptable to the use of an upright rotatable impeller 66 located in the bottom of the tank. As an example, baskets of the type disclosed in 15 Letters Patent of the United States No. 1,905,523 issued April 25, 1933, may be used for this purpose. These dish racks are supported from the support bars 64 by hook members 67 and will slide outwardly over the opened door 14 with the frame 63 20 and the sliding tubes 54.

Slide support brackets 51 and 52 are clamped to the tank 16 by flat headed screws that pass through the bracket and tank wall and screw into clamp plates 69 on the outside of the tank. Rubber pads 70 are set between the enameled surface of the tank and the brackets and between the tank and clamp plates 69 to prevent chipping.

In Fig. 5 is shown means for assembling and holding together the sink portion of the cabinet. 30 The outer surface of the cabinet 10 is usually of a polished or enameled metal. The drain board 12 and back splasher 13 is of linoleum or other sheet material. A firm under structure is provided for the outer portion of the sink top, and this under 35 structure is anchored to the cabinet metal frame 15.

The frame 15 carries the angle bars 72 extending the length of the cabinet. The upper angle bar 72 is attached to an anchoring bar 71 of the 40 frame 15, and is provided with the inwardly extending rabbet portion 74. Over this framework are supported the drain board, sink and back board assemblies which include the wooden frame members 75 around which is anchored the metal 45 sheeting 76 forming a smooth base surface for the resilient padding 77 and the outer surface sheeting 78. These assemblies are firmly cemented together and trimmed with the channel-like strap 79 which extends entirely around the edges of the 50 sink top for this purpose and forms an attractive ledge portion. It will be understood that a watertight connection is had by the structure described.

At the depressed sink portion 11 the exposed edges 84 of these layers of sheeting 76, padding 77 and surface sheeting 78 are finished off in a beveled portion, the cross section of which forms an acute angle with the plane of the under surface of the lowest beveled layer 76.

For the purpose of holding the assemblage together at the exposed portions necessary for the sink and to provide a neat, water-tight and finished appearance at this place, an upper clamping ring 81 is employed. The sink portion 80 has the outwardly extending flange 82 which is suspended from the sheeting 76 by the bolt and nut means 83. A spacing washer 84 is placed between the sheeting 76 and the flange 82 around the bolt 83 to provide a space for the insertion of the clamping member 81. It is preferred to seal the outer 70 edges of sink flange 82 to the sheeting 76 by soldering or otherwise to form a waterproof union, as shown in Fig. 5.

The clamping member 81 is substantially annular in shape and it is to correspond in shape to the upper edge of the sink member. One leg of mem-

ber 81 is firmly secured between the sink flange 82 and the sheeting 77 by the bolt 83 and other leg forms an acute angle with the first mentioned leg sufficient to extend up along the exposed beveled edges of the sheeting 76, the resilient padding 77 and the drain member 78, thereby holding them securely clamped or interlocked at the sink basin edge. This clamping member 81 also serves to provide a neatly trimmed appearance for the sink edge. It is also sealed to flange 82 in a watertight manner.

The inwardly extending rabbeted portion 74 of the upper angle bar terminates in the flange 85. Spaced below the bar 72 is a further channeled box 88 extending across the front of the sink portion of the cabinet and the opening thus provided therebetween is closed by a panel 90. In order to hold the panel 90 in place, there are provided S-shaped clamps 92 adjacent the lower side of the door and spring clamps 94 adjacent the upper edge 20 of the panel. One leg of the S-shaped clamp 92 is attached to panel 90 and the other leg is adapted to engage the rear of bar 88 when the panel is held at a slight forward angle to the cabinet front. The panel is then swung upwardly and inwardly 25 until the spring clamp 94 engages the flange 85 of the angled bar 72.

Various modifications of the embodiment of my invention as described herein are possible without departing from its scope. The present description is presented for purposes of illustration only and is not to be construed so as to limit unnecessarily the scope of the appended claims which are intended to include the various changes and modifications mentioned.

I claim:

1. In apparatus for washing tableware, the combination of a casing structure having an opening in a side wall thereof, a gasket disposed adjacent said opening and carried by the casing structure, a door for closing said opening and hinged adjacent its bottom portion to the casing structure, said door being normally disposed in a vertical position and closing said opening and said door being adjustable to a substantially horizontal position for loading and unloading the apparatus and a support for tableware carried by the casing structure and movable horizontally and exteriorly thereof for loading and unloading said apparatus when the door occupies its horizontal position, said support being disposed above the door when exterior of the casing and the inner side of said door having a projection forming a reservoir and being positioned to engage said gasket when in a vertical position to effect a water-tight sealing of the casing structure and to define a drainage reservoir when in a substantially horizontal position to insure collection of drippings from the tableware.

2. In apparatus for washing tableware, the combination of a casing structure having an opening in a side wall thereof, a door structure for closing said opening and hinged near its bottom portion to the casing structure, said door being normally disposed in a vertical position and closing said opening and said door being adjustable to a substantially horizontal position for loading and unloading the apparatus, a support for tableware carried by the casing structure and movable horizontally and exteriorly thereof for loading and unloading said apparatus when the door occupies the horizontal position, said support being disposed above the door when projecting from the casing, fluid-tight sealing means embodying a gasket carried by one of

the aforesaid structures and an engaging member carried by the other of the aforesaid structures, the part of said fluid-tight sealing means carried by the door structure forming a catch basin on the inner side of the door structure to collect drippings from the tableware when the tableware support is projecting from the casing structure and means cooperating between the door structure and the casing structure for effecting passage of water from the catch basin to the interior of the casing structure when the door is moved in a direction toward closing.

3. In apparatus for washing tableware, the combination of a casing structure having an opening in a side wall thereof, a door structure for closing said opening and hinged near its bottom portion to the casing structure, said door being normally disposed in a vertical position and closing said opening and said door being adjustable to a substantially horizontal position for loading and unloading the apparatus, a support for tableware carried by the casing structure and movable horizontally and exteriorly thereof for loading and unloading said apparatus when the door occupies the horizontal position, said support being disposed above the door when projecting from the casing, means carried by the casing structure for effecting a water-tight sealing of the door with the casing structure, means formed on the inner side of the door for cooperation with said sealing means when the door is closed and for defining a drainage reservoir when said door is in a substantially horizontal position to insure collection of drippings from the tableware, and a trough carried by the casing

structure and extending along the lower edge of the opening to effect collection of drippings and passage thereof to the interior of the casing structure when the door is moved in a direction towards its closed position.

4. In apparatus for washing tableware, the combination of a casing structure having a rectangular opening in the side wall thereof, a gasket carried by the casing structure and extending about all four sides of the opening, a door for closing said opening and hinged to the casing structure, said door being normally disposed in a vertical position and closing said opening and said door being adjustable to a substantially horizontal position for loading and unloading the apparatus, a support for tableware carried by the casing structure and movable horizontally and exteriorly thereof for loading and unloading said apparatus when the door occupies its horizontal position, said support being disposed above the door when projecting from the casing structure, a projection formed on the inner side of the door and extending continuously thereabout to form a drainage reservoir when the door is in a substantially horizontal position for collecting drippings from the tableware, said projection being positioned to engage the gasket when the door is in a vertical position to effect a water-tight closing of the casing structure, and means cooperating between the lower edge of the door and the casing structure to effect passage of drippings from the reservoir to the interior of the casing structure when the door is moved in a direction towards its closed position.

EDGAR S. STODDARD. 35
